UNITED STATES PATENT OFFICE.

SYLVESTER A. GATES, OF DETROIT, MICHIGAN.

METAL-BACK BUILDING MATERIAL.

Application filed February 23, 1926. Serial No. 89,894.

This invention relates to building material, and has special reference to that class of material made from concrete, plaster or other compositions and used in the wall and 5 roof structures of buildings.

The primary object of my invention is to provide composite building material with a metallic backing, which facilitates installing the material, permits the material to be 10 firmly anchored relative to an inner wall or support, protects part of the building material while being handled, and insures a positive and reliable weather proof connection between superposed building material.

15 Another object of my invention is to provide, as an article of manufacture, a channel shaped backing plate in which may be molded and firmly anchored a composite slab, block, tile, shingle or facing piece of 20 composite material susceptible to any desired exterior ornamentation. The anchoring of the material in the backing plate affords a tongue and groove connection with adjacent material and it is by virtue of such 25 connection that the material cannot become laterally displaced after being installed.

A still further object of this invention is to provide a structure composed of an inner wall made of wood, an intermediate wall 30 made of metal, and an outer wall made of composite material, said walls being secured together so as to provide a strong, durable and weather proof structure.

The above are a few of the objects obtained by the construction to be hereinafter described and then claimed, and reference will now be had to the drawings, wherein

40 Figure 1 is a side elevation of a portion of a building wall in accordance with my invention;

Fig. 2 is a vertical sectional view of the same;

Fig. 3 is a perspective view of a slab or block in accordance with this invention;

45 Fig. 4 is a perspective view of a channel shaped metallic backing plate adapted to form part of a slab or block;

Fig. 5 is a horizontal sectional view of a portion of the wall shown in Figs. 1 and 2, and

50 Fig. 6 is a perspective view of a portion of a slab or block showing another form of anchoring member for the slab or block.

The reference numeral 1 denotes a pressed 55 sheet metal backing plate substantially rectangular in elevation and provided with lon-

gitudinal parallel upper and lower flanges 2 and 3. The upper flange 2 is inturned and then outturned so as to form a longitudinal anchoring rib 4 with the outturned portion 60 of said flange of greater depth than the rib 4 so as to form a longitudinal tongue 5.

The lower flange 3 is inturned and then outturned to form a channel groove or seat 6 and this seat serves the office of an anchoring rib, similar to the rib 4, as will appear hereinafter.

The plate 1 has a protruding end 7 apertured or provided with a nail opening 8 for plate securing purposes, and the opposite 70 end of the plate is offset to provide an overlapping flange 9.

Mounted against the back plate 1 in the channel formed by the upper and lower flanges 3 is a composite slab or block 10 that 75 may be molded on the plate 1 and provided with a suitable outer ornamental face. In molding the slab or block the rib 4 and the seat 6 become imbedded and anchored in the upper and lower edges of the slab or block 80 thus preventing lateral displacement of the block relative to the plate and it will be noted that the flanges 2 and 3 cooperate with the plate 1 in protecting the back part of the block. The end 7 protrudes from the 85 block 10, but the block overlaps the flange 9.

As illustrating a sample of an installation of the building material, I show studs 11 and siding 12 as forming an inner wall. A layer or row of the blocks 10 is placed 90 against the inner wall and secured thereto by nails 13. The blocks are placed end to end and consequently the flanges 9 overlap the protruding ends 7 of adjacent back plates, see Fig. 5. Another row or layer of 95 blocks is placed in position on the lower layer or row with the seats 6 receiving the tongues 5, as best shown in Fig. 2, and in this manner an outer composite wall is formed having a metallic backing, constituting an intermediate metallic wall which fully protects the inner wall formed by the siding 12.

When the blocks are of sufficient length the ends thereof may be secured direct to 105 the studding, without using siding, in which instance the back plates afford a metallic side.

Instead of using back plates having protruding ends, I may resort to the construction shown in Fig. 6 where a back plate 14 has one of its flanges 15 cut and outstruck to 110

provide a malleable apertured lug 16 that may be secured to a stud, siding or suitable support. This outstruck lug may be left in the plane of the flange 15 until the block 5 is to be installed and then it may be bent upwardly and easily nailed or otherwise secured to a support. In either instance of anchoring the block relative to a support, driving of a nail does not injure the block 10 and there is plenty of clearance for the manipulation of a hammer or other tool in securing the block in place. It is practically impossible for the concrete or block material to be cracked or injured because of 15 any stresses or strains placed on the back plate when being attached to a support, and with one or more of the lugs at each end of the back plate or at points intermediate the ends thereof, the block may be firmly 20 secured relative to a support.

Obviously during the laying of the building material any sealing material, as paint, tar or the like can be placed on the tongues 5 so that the same will become sealed in 25 the seats 6 and such sealing material may be used at the ends of the blocks, should occasion require. Again, the backing plates may be apertured or cut away to reduce the

weight of said plates and save material. Such other changes as are permissible by 30 the appended claims may be resorted to without departing from the scope of this invention.

What I claim is:—

1. The combination of a composite piece 35 of material having upper and lower edges, a metallic tongue in the upper edge of said piece of material, a metallic seat in the lower edge of said piece of material, and means connecting said seat and tongue independent 40 of said composite piece of material.

2. The combination called for in claim 1, wherein said means is in the form of a plate 45 as a backing for the composite piece of material.

3. The combination of a composite piece of material having upper and lower edges, a metallic tongue in the upper edge of said piece of material, a metallic seat in the lower edge of said piece of material, and a backing plate for said composite piece of material, said backing plate protruding from one end 50 of said piece of material for securing purposes.

In testimony whereof I affix my signature.

SYLVESTER A. GATES.
